VAPOR GENERATOR OPERATION

Charles E. Lucke, New York, N. Y., assignor to
Bailey Meter Company, a corporation of Delaware

Original application November 17, 1931, Serial No.
575,604. Divided and this application January
12, 1935, Serial No. 1,565

18 Claims. (Cl. 122—451)

This invention relates to the proportioning of flowing fluids and forms a division of my co-pending application Serial No. 575,604 filed November 17, 1931, for Regulating valves.

5 In the said co-pending application I have disclosed and claimed a new and novel regulating valve for automatically proportioning the steam to radiant and convection type superheaters of a steam generating boiler, the proportioning of 10 water feed, and for similar usages. I have there- 15 in disclosed but not claimed a novel method and apparatus for proportionally distributing the flow of fluid to a plurality of parallel flow paths in a power producing or utilizing apparatus as well as the method of operating such apparatus, and which method and apparatus I will now cover by more detailed description and will claim by the present specification.

One object of my invention is to provide a 20 method and apparatus for dividing or proportioning a flowing fluid to a plurality of separate paths in desired proportionality or relation.

Another object of the invention is to distribute the liquid supplied to a vapor generator having a 25 plurality of parallel circuits in desired proportionality to the circuits.

A further object is to so distribute the liquid feed to a plurality of parallel circuits of a vapor generator, according to a function of the total 30 flow of liquid feed.

A still further object is to provide a method of 35 operating a vapor generator of the type disclosed, in new and novel manner.

Still another object is to proportion a flowing 40 fluid into a plurality of separate flows according to a dependent or independent variable or a function thereof.

Still further objects will become apparent from 45 the drawings and description forming the specification of my invention.

In the drawings:

Fig. 1 is a somewhat diagrammatic representation in sectional elevation of one embodiment of the invention.

45 Fig. 2 is a sectional elevation of a regulating valve.

Fig. 3 is a somewhat diagrammatic sectional elevation of a second embodiment of my invention.

50 Fig. 4 is a somewhat diagrammatic representation of a further embodiment of my invention in connection with a once-through boiler.

Fig. 5 is a sectional elevation of a fragment of a regulating valve.

55 Fig. 6 is a sectional view taken along the line

6—6 in the direction of the arrows of the regulating valve illustrated in Fig. 4.

Fig. 7 is a section through the regulating valve of Fig. 1 along the lines 7—7 in the direction of the arrows.

The drawings as a whole are a duplication of the drawings of my co-pending application Serial No. 575,604 of which the present specification is a division.

The embodiment illustrated diagrammatically 10 in Fig. 1 relates to a vapor generator, such for example as a steam boiler that is provided with two superheaters, one of which may be heated by radiant heat from the boiler furnace and the other heated by contact with the hot gases of 15 combustion passing over it. The steam passing through the respective superheaters is desirably so proportioned that the proper degree of superheat can be obtained regardless of variations in the load. The steam from the steam drum of the 20 boiler is caused to pass through the two superheaters in parallel. The most or all of the steam is caused to pass through the radiantly heated superheater at low ratings, and larger proportions of the steam are passed through the other super- 25 heater at higher ratings.

Reference character 1 indicates the furnace of a steam generating boiler generally indicated at 2, having a steam and water separating drum 3, to which is connected a conduit 4 for the discharge of the steam. A superheater 5 which may be termed a convection superheater is located to be heated by the hot gases of combustion sweeping over it, while a superheater 6 commonly termed a radiant superheater is located to be 30 heated by the radiant heat from the furnace 1, to which fuel for combustion is fired through any conventional burner 7, or otherwise, depending upon the nature of the fuel.

The conduit 4 leads to the inlet of a two-way 40 valve 8, having an outlet 9 communicating by means of a pipe 10 with the radiant superheater 6, and an outlet 11 communicating by means of a pipe 12 with the superheater 5. The outlets of the two superheaters are connected to a main 45 steam header 13 through the pipes 14 and 15.

As is well known, a characteristic of radiant heat superheaters is that the temperature of the steam leaving the superheater decreases with an increase in the rate of steam flow therethrough, 50 whereas the temperature of the steam at the outlet of a convection type superheater, such as is indicated at 5, increases with an increase in the rate of steam flow therethrough. It is apparent therefore that by having a portion of the steam 55

which is generated by the boiler pass through the radiant heated superheater and the remainder pass through the convection type superheater, and by increasing the proportion of the steam which 5 passes through the superheater 5 as the rate of steam output increases, the proper amount of superheat may be maintained in the header 13 regardless of the rate of operation of the boiler. The valve which I indicate generally at 8, and 10 whose peculiar design and function is claimed in my referred to co-pending application, will automatically so divide the steam discharged by the boiler through the two superheaters as to maintain the proper steam temperature at the header 15 13, which temperature may be held constant throughout the range of output of the boiler or may be caused to vary in any manner desired.

In a casing 16 of the valve 8 is an upper cylindrical member 17, the lower end of which is serrated as indicated at 18 and which when positioned axially of the casing across the outlet 9 serves to control the flow of fluid therethrough. A lower cylindrical member 19, the upper end of which is serrated as indicated at 20, controls the flow of 25 fluid through the outlet 11. The upper member 17 is spaced from and held relative to the lower member 19 by a rod 21 screw-threaded into a closed head provided at the lower end of the lower member 19 as at 22, the said rod 21 being 30 threaded through a spider 23 normal to the axis of the upper member 17.

The lower portion of the casing 16, together with a connecting pipe 24, and a chamber 25, form a U-tube containing a liquid such as mercury 35 for example generally indicated at 26. The chamber 25 communicates with the steam header 13 through a pipe 27. The assembly comprising the cylindrical member 17, the cylindrical member 19, and the rod 21, are free to move axially in the casing 16; the member 19 being kept from rotation within the casing 16 through the agency of a spline 28. The lower head 22 of the member 19 rests upon the surface of the mercury 26 and is caused to rise and fall within the casing 16 upon 45 variation in elevation of the mercury within the casing 16.

As is well known, upon an increase in the rate of steam output from the boiler the pressure drop through the superheaters between the conduit 4 and the header 13 will increase, while with a decrease in the rate of steam output the pressure drop will decrease. Inasmuch as the pressure of the steam in the conduit 4 is effective upon the surface of the mercury in the casing 16, and the 50 pressure of the steam in the header 13 is effective upon the surface of the mercury in the chamber 25, a variation in pressure between the steam in the conduit 4 and the steam in the header 13 will cause a variation in level of the mercury in the 55 two legs of the U-tube in a well-known manner. Thus for an increase in rate of discharge of steam from the boiler, the level of mercury within the casing 16 will tend to fall while the level of the mercury within the chamber 25 will tend to rise, 60 with a resulting lowering of the movable parts of the valve 8, namely, the members 17 and 19 and their connecting rod 21.

It will be noted that the arrangement of Fig. 1 is that of no steam being discharged from the 65 boiler and correspondingly no pressure differential existing between the conduit 4 and the steam header 13. The absence of a pressure differential across the U-tube, comprising the casing 16, the connecting pipe 24, and the chamber 25, results in 70 the mercury 26 being at the same level in both

legs of the U-tube corresponding to a zero position, and the movable parts of the valve assembly in one extreme of their travel.

In operation, as the rate of steam discharged from the boiler through the conduit 4 increases, the pressure differential between the boiler and the header 13 increases, with a resulting lowering of the mercury within the casing 16 and lowering of the valve assembly whereby the passage to the outlet 9 is decreased, while the passage to the outlet 11 is increased; for in lowering the member 17 its ports become less effective for passage of steam to the outlet 9, while the ports of the member 19 become more effective for passage of the steam to the outlet 11. Thus with an increase 15 in the rate of output of steam from the boiler a lesser percentage of the steam will flow through the radiant superheater 6, while a greater percentage will flow through the convection superheater 5, as is desired. The result is a temperature of steam in the header 13 in desired relation to the rate of output of the boiler.

The pressure drop through the superheaters between the conduit 4 and the header 13 bears a functional relation to the rate of steam flow 25 therethrough, as does the relation between the temperature at the outlet of the superheaters and the rate of steam flow therethrough, which relation may vary with different boilers. It is therefore desirable to provide means for modifying the motion of the valve member within the casing 16 in response to changes in the pressure drop so that regardless of the relationship existing between such factors, the proper amount of superheat can be maintained in the total steam 35 passing from the boiler. As a means of so modifying the motion of the valve members, which I accomplish by modifying the rise and fall of mercury within the casing 16, I have shown a displacer 29 which may be of a desired shape, 40 positioned within the chamber 25 by means of a screw threaded rod 30 and having a hand wheel 31 for raising and lowering it.

The displacer 29 acts to progressively vary the cross-sectional area of the chamber 25 to modify 45 the proportion of the total mercury deflection in the U-tube which takes place in that leg of the U-tube. I further employ in the chamber 25 a submerged displacing member 32 taking the form of a screw threaded rod passing through the wall 50 of the casing 25, and always submerged in the mercury 26, to the end that the zero pressure differential level of the mercury in the two legs of the U-tube may be varied by screwing the displacing member 32 further in or further out of 55 the interior of the chamber 25, thus displacing more or less of the mercury 26.

As a further form of adjustability of the regulating valve I have shown a hand wheel 33 connected to a rod 34 having its lower end forked 60 as at 35 for engagement with holes in the spider 23, whereby rotation of the hand wheel 33 causes rotation of the cylindrical member 17 relative to the screw threaded rod 21. A result of such rotation of the hand wheel 33 is that the member 17 will be positioned axially closer to or further from the member 19, thus varying the basic spacing of the members and of the port openings opposite the discharge passages 9 and 11. By the construction shown I may vary the relative spacing of the members 17 and 19 along the rod 21 70 while fluid is flowing through the regulating valve, making such adjustment external by means of the hand wheel 33 and without in any way inter- 75

ferring with the axial movement of the valve assembly within the casing 16.

It will be seen that through the instrumentality of the adjusting hand wheel 33 and the displacing member 32 I may vary the proportionality between the discharge 9 and 11, while through the shape and position of the displacing member 29 I may make the proportionality follow a functional or desired relation with the rate of flow 10 of steam through the conduit 4 from the boiler.

In Fig. 1 I have purposely shown the regulating valve assembly to much larger scale than the boiler and boiler piping to make clear the features of my invention. I show in Fig. 7 a section 15 through the valve assembly above the spider 23 to show clearly the formation of the spider across the member 17 and the engagement therewith of the fork 35 for turning the member 17 on the screw threaded rod 21.

20 I show in Fig. 2 a valve assembly which is similar to the assembly of Fig. 1, in that a fluid entering the casing through one opening, such as is indicated at 36, is proportioned in its exit through the discharge passages 31 and 38 by a 25 regulating valve assembly having members 39 and 40 spaced apart upon a rod 41, the assembly resting upon the surface of mercury or other liquid in one leg of a U-tube of which the valve casing forms a part and positioned in the valve 30 casing upon variation in level of the mercury within the U-tube. In Fig. 2 however I illustrate the valve construction without means of varying the spacing of the members 39 and 40, as well as without any displacement members in the other 35 leg of the U-tube.

In Fig. 5 I have illustrated a section through a fragment of a regulating valve assembly wherein in the ports of the serrated end of the cylindrical member such as that of 42 are curved or shaped 40 to take into account a variable discharge of fluid through the ports in relation to axial movement thereof, and in desired relationship thereto to compensate for characteristics or relationships as desired.

45 It is not essential to the functioning of my invention that the pressure differential effective upon the surfaces of the mercury in the U-tube be that of the same fluid which is flowing through and proportioned by the regulating valve. In 50 Fig. 3 I show a regulating valve generally indicated at 43 of similar construction to the valve 8 of Fig. 1, but wherein the valve casing is partitioned off from the U-tube by a partition such as indicated at 44, while the rod 45 upon which are 55 carried the two valve members 17A and 19A extends through the partition 44 to engage a piston part 46 cooperating in a cylinder 47 forming one leg of the U-tube, of which a chamber 48 forms the other leg connected through a pipe 49. The 60 U-tube 47, 48, 49 contains mercury and applied across the U-tube is a pressure differential bearing a known relation to the rate of fluid flow through a conduit such as 50, in which is positioned a flow nozzle 51 or other pressure difference creating device. At opposite sides of the 65 flow nozzle 51 to the conduit 50 are connected pipes 52 and 53 joining respectively the low pressure leg 48 and the high pressure leg 47 of the U-tube.

70 In operation, when fluid flowing through the conduit 50 in the direction of the arrow increases as to rate of flow, the pressure differential across the flow nozzle 51 increases, whereby a greater relative pressure is effective within the chamber

75 47 than through the pipe 52 upon the mercury in the chamber 48, causing the mercury in the chamber 47 to lower in its level and the mercury in the chamber 48 to rise in its level, thereby resulting in a positioning of the valve mechanism within the casing 43 downwardly. When the rate of flow of fluid through the conduit 50 tends to decrease, the reverse is true, and the valve mechanism within the casing 43 will be moved upwardly. 10

In general the construction illustrated in Fig. 3 is that of moving the valve proportioning means relative to the discharge openings from the valve casing in accordance with a measure of the rate of flow of a fluid other than that which is passing 15 through the valve casing.

In Fig. 4 I depict an apparatus wherein I desirably proportion a flowing fluid to more than two discharge openings of the valve casing. For example, water being fed to the parallel circuits 20 54, 55 and 56 of a once-through boiler indicated generally at 57, is so proportioned through the agency of a regulating valve 58 supplied by a conduit 59.

The supply of water to the conduit 59 may be 25 from a pump or header system, and the total flow of water to the boiler may be controlled before such water reaches the regulating valve 58, so that the regulating valve 58 serves not to control the supply of water to the boiler as a whole but 30 to control the proportioning of such water which is supplied to the boiler between the three circuits 54, 55 and 56.

The water being fed through the conduit 59 passes through a pressure difference creating 35 device, such as a flow nozzle 60, whereby a pressure difference is created across the nozzle which bears a known relation to the rate of flow of fluid therethrough. This pressure difference is transmitted through pipes 61 and 62 to the high and 40 low pressure sides respectively of a U-tube wherein the level of a sealing liquid such as mercury is varied for the axial positioning of the regulating valve members within the casing 58 to result in a proportioning of the water flowing through 45 the conduit 59 to the parallel circuits of the boiler 57 in desired manner.

It will be seen that I provide in this embodiment means for introducing functional relation between rate of fluid flow and proportionality of 50 discharge, as well as means for adjusting the initial proportionality of discharge, or port opening with no discharge, and further that I may vary the relationship of the three cylindrical valve members relative to the discharge ports by 55 spacing them closer together or further apart upon the rod to which they are held.

In effect I may cause the water fed to the boiler 57 to be proportioned equally among the circuits of the boiler, or in desired proportionality between 60 the circuits in a manner which may depend upon the proportion of heating area embodied in the different circuits or the portion of heating area which is exposed to different degrees of temperature within the furnace or boiler passes. Furthermore it may be proportioned according to the 65 relation of the heating areas of the different circuits exposed to radiant or convection heating, or to a combination of the two.

In Fig. 4 the arrangement of the three cylindrical valve members is illustrated as giving fixed 70 proportionality between the three pipes 54, 55 and 56. This differs from the arrangement of Fig. 3 for example, wherein the cylindrical members 17A, 19A have their serrated ends opposed 75

axially of the valve casing so that as the valve assembly moves downward the port opening of the member 17A becomes less effective, while that of the member 18A becomes more effective, and vice versa as the assembly moves upward.

In general I have illustrated and described my invention in connection with a regulating valve or means for the dividing or proportioning of a flowing fluid in definite ratio or functional proportionality, or in desirable accordance with the magnitude of a variable. The apparatus is provided with means of adjustment for varying the proportionality and which may have embodied in it means for correcting for undesirable characteristics or for compensating for known laws.

The apparatus provides means for carrying out the new and novel methods of my invention in proportioning of a flowing fluid to a plurality of paths in accordance with a variable or a function of a variable.

It will be understood by those skilled in the art that the illustrations which I have shown and described may form only preferred embodiments of my invention and that I am not to be limited thereby except as to the claims in view of prior art.

What I claim as new, and desire to secure by Letters Patent of the United States, is:

1. The method of operating a vapor-generator having a plurality of once-through fluid conduits in parallel, each receiving liquid at one end and delivering superheated vapor at the other and heated by a furnace, which includes establishing a desired proportionality of inflow of liquid between the plurality of conduits for a certain rate of operation, and automatically varying said proportionality throughout the range of operation of the generator.

2. The method of operating a vapor-generator having a plurality of once-through fluid conduits in parallel, each receiving liquid at one end and delivering superheated vapor at the other and heated by a furnace, which includes establishing a desired proportionality of inflow of liquid between the plurality of conduits for a certain rate of operation, obtaining a measure of total liquid inflow, and utilizing such measure for automatically varying such proportionality throughout the range of operation of the generator.

3. The method of operating a vapor-generator having a plurality of once-through fluid conduits in parallel, each receiving liquid at one end and delivering superheated vapor at the other and heated by a furnace, which includes establishing a desired proportionality of inflow of liquid between the plurality of conduits for a certain rate of operation, obtaining a measure of generator operation, and utilizing such measure for automatically varying such proportionality throughout the range of operation of the generator.

4. In combination, a vapor-generator and heating means therefor, said vapor-generator comprising a multiplicity of long, small-bore, parallel once-through conduits each receiving a forced flow of liquid at one end and delivering vapor only at the other end, means for measuring the total liquid inflow to all of the conduits, and means for maintaining liquid feed to the conduits in desired proportionality, said last-named means positioned responsive to movement of said first-named means.

5. The method of operating a vapor-generator having a plurality of parallel fluid paths and heated by a furnace, which includes establishing a desired proportionality of fluid flow between the

plurality of paths for a certain rate of operation, and automatically varying said proportionality throughout the range of operation of the generator.

6. The method of operating a vapor-generator having a plurality of parallel fluid paths and heated by a furnace, which includes establishing a desired proportionality of fluid flow between the plurality of paths for a certain rate of operation, obtaining a measure of total fluid flow, and utilizing such measure for automatically varying said proportionality throughout the range of operation of the generator.

7. The method of operating a vapor-generator having a plurality of parallel fluid paths and heated by a furnace, which includes establishing a desired proportionality of fluid flow between the plurality of paths for a certain rate of operation, obtaining a measure of generator operation, and utilizing such measure for automatically varying such proportionality throughout the range of operation of the generator.

8. The method of operating power producing or utilizing apparatus having a plurality of parallel fluid flow paths, which includes establishing a desired proportionality of fluid flow between the plurality of paths, obtaining a measure of total fluid flow, and utilizing such measure for automatically varying such proportionality throughout the range of operation of the apparatus.

9. The method of operating power producing or utilizing apparatus having a plurality of parallel fluid flow paths, which includes obtaining a measure of total fluid flow, and utilizing such measure for proportioning the total fluid flow to the plurality of paths.

10. The method of operating a vapor-generator having small liquid storage and a high rate of evaporation and having parallel vapor flow paths, which includes measuring total vapor generated, and utilizing such measure for proportioning the total vapor flow to the plurality of paths.

11. The method of operating a vapor-generator having small liquid storage and a high rate of evaporation and having parallel vapor flow paths, which includes proportioning the vapor generated to the vapor flow paths according to rate of generator operation.

12. The method of operating a vapor-generator having a plurality of parallel fluid paths and heated by a furnace, which includes establishing a desired proportionality of fluid flow between the plurality of paths for each rate of operation, obtaining a measure of total fluid flow, and utilizing such measure for automatically maintaining said proportionality throughout the range of operation of the generator.

13. The method of operating a vapor-generator having a plurality of parallel fluid paths and heated by a furnace, which includes establishing a desired proportionality of fluid flow between the plurality of paths for each rate of operation, obtaining a measure of generator operation, and utilizing such measure for automatically maintaining said proportionality throughout the range of operation of the generator.

14. The method of operating a vapor-generator having a plurality of parallel fluid paths and heated by a furnace, which includes the step of maintaining the total flow resistance of each path substantially constant throughout the range of generator operation.

15. A method of operating a vapor-generator having a plurality of parallel fluid paths and heated by a furnace, which includes the step of

maintaining the total flow resistance from liquid inlet to vapor outlet substantially constant throughout the range of generator operation.

16. The method of operating power producing or utilizing apparatus having a plurality of parallel fluid flow paths, which includes continuously obtaining a measure of rate of operation of the apparatus, and utilizing such measure for proportioning the total fluid flow to the plurality of paths.

17. In combination, a vapor-generator and heating means therefor, said vapor-generator having a plurality of parallel fluid paths, means

for measuring the total fluid flow, and means positioned by said last named means and adapted to proportion the fluid through the several paths in desired proportionality.

18. The method of operating a vapor-generator having a plurality of heated parallel fluid flow paths, which includes establishing a desired different proportionality of fluid flow between the plurality of paths for each rate of generator operation, and maintaining such proportionality throughout at least a portion of the range of generator operation.

CHARLES E. LUCKE.
